WORK HOLDER AND METHOD FOR
MAKING ROPE SOLES

Camillus C. Enright, Trenton, N. J.

Application March 5, 1945, Serial No. 581,105

7 Claims. (Cl. 112—2)

1

This application is a continuation in part of my copending application which has issued as Patent No. 2,370,642 on March 6, 1945.

My invention relates to the manufacture of rope soles for footwear, mats, pads and other articles formed of strands or coils of rope, braid or other fibrous material, and to machines and methods for use in stitching such materials.

Most rope soles and similar articles have been made heretofore by hand or by machines which are slow in operation. Furthermore, it has not been possible when using machines for stitching such materials to locate the stitches accurately with respect to the work so as to insure the passage of a stitch through ends or turns of the coiled rope or strands of material or to position the stitches in other selected and varied locations to insure the strongest and most satisfactory product.

When forming rope soles it has also been usual to clamp or press the strands together in a forming device and thereafter to transfer the assembled coils or strands to another device which supports the material during the stitching operation. This transfer of the material from one device to another necessarily results in some loosening or expansion of the strands so that they are not always compressed or held together in the same manner when stitched as when initially compressed. In other prior constructions the assembled strands have been held in place by pressure applied to the opposite faces of the article and in a direction normal to the plane in which the strands are to be stitched. This pressure further tends to loosen the strands so that the strands are not properly compacted in the finished stitched product.

In accordance with my invention these objections to constructions and methods of the prior art are overcome and means are provided which are rapid in operation and serve to permit variation in the spacing and accurate location of the stitches in the work. My invention further provides methods and means which serve to compress the material in a direction parallel to that in which the stitches are formed and to hold the material so compressed during stitching thereof so that the finished product remains firm and tight when pressure is relieved after stitching.

In the construction illustrated in the drawings and hereinafter described, the machine embodies a workholder which is adapted to receive strands or coils of rope to form a rope sole. The material is placed in the workholder and is compressed transversely of the coils or strands in a direction

2

parallel to that in which the work is to be stitched. The workholder carrying the compressed strands is then moved in successive steps past a reciprocating needle to stitch the material. The length of each step and the position of each stitch is controlled to space the stitches different distances apart and to locate these stitches in predetermined portions or at different points in the work so that the stitches pass through ends, turns or other predetermined portions of the work. The length and position of each stitch is determined independently of every other stitch and it is therefore possible to pass workholders carrying material for forming soles of different sizes or for forming different articles, one after another through the machine and past the needle and to stitch each article in a selected and predetermined manner without change or adjustment in the machine or its various elements.

10 One of the objects of my invention is to provide improved means for use in stitching stranded material to produce soles for footwear, mats, pads and other articles formed of fibrous material.

15 A further object of my invention is to provide novel means for controlling the position in which stitches are formed in articles such as rope soles, mats, pads and other articles.

20 Another object of my invention is to provide improved methods for stitching rope soles and similar products.

25 A further object of my invention is to provide novel means for forming and holding work to be stitched.

30 These and other objects and features of my invention will appear from the following description thereof in which reference is made to the figures of the accompanying drawings.

In the drawings:

35 Fig. 1 is a side elevation of a preferred form of workholder embodying my invention with parts thereof broken away.

40 Fig. 2 is a top plan view of a portion of the form of workholder illustrated in Fig. 1.

45 Fig. 3 is a vertical sectional view of the workholder illustrated in Fig. 1.

50 Fig. 4 is a vertical sectional view through the workholder shown in Figs. 1, 2 and 3 showing the work in place with respect to a needle and shuttle used in forming a stitch, and

55 Fig. 5 is a side elevation of a portion of two adjacent workholders indicating the manner in which the stitches are formed in passing from one workholder to another.

In that form of my invention chosen for illustration and shown in the drawings the work-

holders are designed to be passed through a machine such as that illustrated and described in my copending application upon which Patent No. 2,370,642 has recently been issued to form stitches in the work carried thereby. The workholders may be of any suitable shape or form depending upon the type of article to be produced. As shown the holder is employed for forming rope soles for footwear and is formed of two members 2 and 4 which are separable along a line extending longitudinally of the sole to be produced. The upper member 2 and the lower member 4 present complementary inwardly facing surfaces which define the shape of the article to be produced. These members extend about the coils or strands of material 6 to be stitched and are movable toward each other to compress the strands of material transversely of the sole and in the direction in which the sole is to be stitched.

Each of the members 2 and 4 is formed with longitudinally extending beams or tracks 8 and 10 on the opposite outer faces of the section and adjacent the longitudinal axis of the holder. These tracks are connected together at their ends by transversely extending webs 12 and pins 14. The opposite faces of the holder which lie adjacent the upper and lower faces of the sole are preferably spaced apart a distance at least equal to the uncompressed thickness of the sole to be produced so that the holder can readily receive the stranded material. By holding the faces thus spaced apart the strands of material are substantially uncompressed in directions normal to the upper and lower faces of the sole and therefore there are no forces opposing compression of the strands in the direction in which they are to be stitched and the strands are not expanded or spread transversely by pressure applied to the faces of the sole. These faces are formed by the ribs 16 which extend vertically from the tracks 8 and 10 toward the edges of the holder. The ribs which form the faces of the workholder are fixedly secured to the tracks 8 and 10 and held in spaced relation by the webs 12 and pins 14, whereas the edges of the holder which lie adjacent the outer convolutions or strands of the material used in producing the sole are formed as inwardly turned extremities 18 on the ends of the ribs 16. The extremities 18 are formed with openings 20 therein through which a needle 22 or other stitch forming means may be passed into engagement with the work in the holder. The extremities 18 are also formed with longitudinally extending slots 24 therein which join the openings 20 and permit the passage of stitch-forming thread into engagement with the work.

Preferably also the extremities 18 are formed with inwardly turned projections 26 which serve to compress the material adjacent the slots 24 and in the plane in which the stitches are to be produced to a greater extent than the material is compressed adjacent the ribs 16 and on the opposite faces of the sole. This serves to locate the stitch forming thread in a marginal groove or recess extending longitudinally of the sole so that it is not exposed prominently in the finished product.

In order that the work may be molded or shaped prior to stitching and remain firm and tight during stitching so as to retain its molded shape and firm character after stitching and when removed from the workholder, the members 2 and 4 of the holder are provided with telescoping portions 28 which guide the members in their movement toward each other to compress the material transversely of the strands and in a

direction parallel to that in which it is to be stitched. The lower end of the portion 28 on the upper member 2 is engageable with the upper surface of the tracks 8 and 10 on the lower member 4 to limit movement of the members toward each other and thus prevent undue compression of the work, and to accurately define the size of the shoe sole to be produced. After being forced together about the work and into the fully closed and strand compressing position shown in Figs. 3 and 4 the members are locked together and held in place by means of hooks 30 on the ends of the members which are movable to engage the pins 14 on the opposite member. When so locked and held in place the members and work are moved past the needle 22 which cooperates with a shuttle 32 to form stitches in the work.

It will be noted that there is an opening 34 between the hook 30 and the web 12 on the holder. Moreover, the extremities of the tracks 8 and 10 project beyond the end face of the hook 30 to provide an opening 36 between one holder and another when they are placed end to end and passed in succession through the sewing machine. These openings are provided to permit the formation of stitches about the web 12 and hook 30 so that when the stitches are thereafter cut between the successive holders, loose ends of thread are presented which may be used for finishing the sole or other article. The position of the threads about the webs 12 and hooks 30 of adjacent workholders is indicated in Fig. 5 where the thread 38 is that carried by the needle and extends over the web 12 and hook 30 whereas the thread 40 is that carried by the shuttle and passes beneath the web 12 and hook 30 and through the loop in the thread 38 which forms the stitch.

In forming these stitches the needle 22 passes through the openings 20 in the edges of the holder adjacent extremities 18 while the threads 38 and 40 pass through the slots 24 between the extremities 18 and lie in the groove formed in the edges of the work by the inwardly turned projections 26 on the extremities 18. By cutting the thread at the ends of the workholder where it passes through the opening 36 the holders are cut apart and the free ends of the threads 38 and 40 are available for finishing the adjacent ends of the articles in adjacent workholders.

It is important in many instances to position the stitches accurately with respect to the work and by controlling the position of the stitches it is possible to insure passage of a stitch through any particular portion of the material being stitched. Thus when forming a shoe sole of the type shown and described in my issued Patent No. 2,430,497 and shown in Fig. 5 of this application, it is possible to place stitches in the work so that they extend through terminal portions such as the ends or reversely turned folds or coils of the rope or braid used in forming a shoe sole. As illustrated in Fig. 5 the rope sole may have reversed turns or terminal portions 41, 42 and 44 and may have an end portion 46 through which it is desired to pass stitches in order to insure the formation of a strong, durable product. Stitches are, of course, passed through the sole at various other points although the positioning of the latter stitches is not generally of such importance. However, even then it is frequently desired to space the stitches different distances apart as when stitching the shank portion and toe or heel portions of the sole.

The desired positioning and spacing of the stitches in the work is accomplished in accord-

since with my invention by suitably positioning the terminal portions of the stranded material with respect to the work holder and by controlling the movement of the workholder with respect to the stitch forming means or needle 22.

When using a sewing machine of the type shown and described in my issued Patent No. 2,370,642 of which this is a continuation the tracks 8 and 10 are formed on their opposite outer faces with ratchet teeth 48 and 50 which extend longitudinally of the path of movement of the workholder through the machine and face in opposite directions. The teeth 48 on track 8 are used to advance the workholder and to prevent recoil of the holder whereas the teeth 50 on track 10 are used to limit the forward movement of the workholder and to control the length of each step and the position of each stitch in the work. The length of the ratchet teeth 50 and preferably also the length of the teeth 48 are varied to correspond to the distance that the stitches are to be spaced in the work. The position of the ends of the ratchet teeth 50 further serve to determine the position in which a stitch is formed in the work.

The ratchet teeth 48 and 50 are respectively engaged by pawls or other actuating means 52 and 54 for advancing the workholder through the sewing machine. These pawls are reciprocated parallel to the tracks 8 and 10 during operation of the sewing machine as described more fully in my Patent No. 2,370,642. In this way the pawls are caused to engage each successive ratchet tooth on the tracks 8 and 10 so as to advance the workholder step by step past the stitching means, and the length of each step is determined by the length of the ratchet teeth and corresponds to the spacing of the openings 20 in the edge of the workholder. Therefore even though the openings 20 in the edge of the workholder are spaced different distances apart the holder is moved so that each successive opening is positioned opposite the needle 22 so as to permit the needle to pass therethrough and through a predetermined portion of the stranded material in forming a stitch. Thus for example, the openings in the holder are laid out so as to conform to the design of the sole to be produced and the locations of the ratchet teeth 48 and 50 are established to coincide with the openings. Thereafter, the reversely turned point 42 in the stranded material may be positioned in the holder in line with the end face of the ratchet tooth 51 and if the engaging end of pawl 54 is opposite the needle 22 the stitch will be placed so as to pass through the point 42. The holders are guided in their movement past the needle 22 by means of the flanged rollers 56 which are mounted on stationary axles 55 carried by the frame 57 of the sewing machine. The rollers are located on opposite sides of the workholder and bear against the upper surfaces of the tracks 8 and 10 on the upper member 2 of the workholder and against the lower surfaces of the tracks 8 and 10 on the lower member 4 of the workholder. The rollers 56 are spaced vertically so as to urge the members together to a fully closed position in which the portion 28 on the upper member 2 bears against the upper faces of the tracks 8 and 10 of the lower member 4. In this way the rollers 56 serve to insure proper compression of the work during the stitching operation and overcome any tendency for the members 2 and 4 to spring apart or to be bowed at the center due to compression of the stranded material. At the same time, compression of the work is limited by engagement of

the portions 28 against the upper face of the tracks 8 and 10 on the lower section so that the material is not unduly compressed and the size of the finished stitched sole is definitely established.

With this construction the material carried by the workholder is stitched while under compression transversely of the strands of material and transversely of the sole, and the stitches are accurately placed with respect to the material so as to pass through the terminal portions or other predetermined parts of the work by controlling the movement of the workholder and work with respect to the needle or other stitch forming means employed. However, the movement and positioning of the workholder may be effected by any suitable or preferred means desired without departing from my invention.

The operations employed when using the workholders described to produce rope soles for foot-wear will be apparent from the foregoing description. The strands of rope, braid or other fibrous material are coiled or otherwise arranged in superposed relation in the general shape of the sole to be made and are placed within the cooperating members 2 and 4 of the workholder. The ends of reversely turned parts 41, 42, and 44, and the ends 46, or other terminal portions of the stranded material are arranged in predetermined positions within the workholder in coiling or assembling the strands of material to be stitched. The sections 2 and 4 of the workholder are then forced toward each other whereby the inwardly turned projections 26 on the extremities 18 of the ribs 16 engage the edges of the strands of material and compress the strands transversely to compact the material and shape it for stitching. The members are moved together until the lower ends of the portions 28 on the section 2 are in contact or substantially in contact with the upper face of the tracks 8 and 10 on the section 4 so that the material cannot be overcompressed and the size of the shoe sole or article to be produced is fixed and controlled by the workholder. The sections after being forced together are locked in place about the work by moving the pivoted hooks 30 into engagement with the complementary pins 14 on the opposite section of the workholder. In this way the material is shaped and compressed transversely of the convolutions or strands of the coil and transversely of the sole and in a direction parallel to that in which the material is to be stitched. Furthermore, the inwardly turned projections 26 located on the extremities 18 form a groove in the edge of the sole for receiving the threads 38 and 40.

The workholder carrying the work is then moved past the needle 22 or other stitch forming means and the tracks 8 and 10 on the sections of the mold are engaged by the rollers 56 on the sewing machine so that the rollers aid in forcing the sections of the workholder together and perform any further compression of the work necessary to insure proper formation of the sole.

The workholder is positioned with respect to the needle so that each stitch may be properly positioned and spaced from preceding and following stitches by any predetermined or desired interval. Furthermore, the movement of the workholder is controlled to insure the formation of stitches which pass through the ends, reversely turned parts or other terminal portions of the stranded material within the work.

On reaching the end of the workholder, stitches are formed about the web 12 and hook 30 on the

end of one workholder and about the hook 30 and web 12 of a succeeding workholder being fed through the machine and stitching of the work in the next holder proceeds in the same manner. The stitches formed about the webs 12 and hooks 30 are free stitches and do not engage any work so that after the workholders have passed beyond the needle 22 they are connected one to another by the free stitches, but may be cut apart by severing the thread between the ends of successive workholders in space 36. In this way free ends of thread are available for binding off and finishing the adjacent ends of the stitched products.

When the work has been stitched in this manner it may be removed from the workholder by swinging the hooks 30 outward from engagement with the pins 14 on the complementary section of the holder and the stitched sole may then be finished while the workholders are returned for receiving and compressing coiled material for forming additional soles.

In forming soles in accordance with my invention the shape and size of succeeding workholders and of the work produced therein may be varied if desired while operating continuously and it is not necessary to readjust or alter the machine in any way in order to form shoe soles of different sizes or in order to form right and left soles for shoes. Moreover, the soles may be quickly and accurately produced and the resulting product is strong, firm and accurate in size and shape due to the fact that it is maintained under compression throughout the forming and stitching operations.

It will be apparent that the work holder may be used for shaping and compressing stranded materials which are to be secured or bonded together by means other than thread. The work holder also may be employed for shaping and compressing loose or irregularly arranged bats or masses of fibrous materials which are to be stitched, sewn or bonded together into a predetermined form.

While I have illustrated and described workholders for use in forming soles for footwear in accordance with my invention it will be apparent that other articles may be produced in the same manner and that the form, construction and arrangement of the holders and of the strands of material therein, as well as the stitch forming means and the means for moving the holders and work relative thereto, are each capable of numerous changes and modifications without departing from the spirit and scope of my invention. In view thereof it should be understood that the preferred embodiments of my invention shown in the drawings and herein described are intended to be illustrative and are not intended to limit the scope of my invention as defined by the following claims.

I claim:

1. A holder for receiving material such as coiled rope, braid or the like for the manufacture of flat articles such as rope soles, mats and pads, said holder being formed with separable sections shaped to extend about the edges of a coil of material and provided with openings in the opposite edges thereof for the passage of a needle through the material, and means located adjacent said openings projecting inward from adjacent portions of said sections for compressing the material adjacent said openings in a direction parallel to that in which the needle is passed through said openings and to a greater extent

than other material engaged by said portions are compressed.

2. The method of producing soles for footwear formed of stranded material which comprises the steps of arranging the strands side by side in the general form of a sole for footwear, compressing said stranded material transversely of said strands and in a plane parallel to and substantially mid-way between opposite upper and lower faces of said sole to a greater extent than in planes including said upper and lower faces of said sole, and forming stitches in said stranded material in the first mentioned plane while the stranded material is so compressed.

3. A workholder for receiving and holding strands of material during stitching thereof to produce soles for footwear, said holder comprising complementary members each having side portions fixedly connected together and held in spaced relation to form a cavity for receiving the strands to be stitched and provided with edge portions secured to said side portions and presenting surfaces defining the edges of the sole to be produced, said surfaces having openings therein positioned to allow the passage of a needle therethrough into engagement with material within the holder and having slots connecting said openings through which stitch forming threads may be passed, said complementary members being movable toward each other to compress the stranded material therein in the direction in which it is to be stitched, and means extending inward from said edge defining surfaces adjacent the opposite edges of said slots to compress the material adjacent said slots to a greater extent than other material engaged by said surfaces.

4. A workholder for use in stitching stranded material to produce soles for footwear comprising separable sections each presenting a portion defining one longitudinal edge of the sole to be produced, said portions being provided with complementary openings spaced different but predetermined distances apart longitudinally of the workholder whereby stitches may be formed different but predetermined distances apart in the stranded material, and means carried by said workholder and spaced apart different but predetermined distances corresponding to the spacing of said openings in the edge defining portions of the holder for positioning each opening adjacent a stitch forming device.

5. A holder for receiving material such as coiled rope, braid or the like for the manufacture of flat articles such as rope soles, mats and pads, said holder being formed with separable complementary sections each formed with a portion shaped to extend about an edge of material in said holder and provided with openings in said portion for the passage of a needle therethrough into work within the holder, said sections being movable toward each other to compress material between said portions in the direction in which the material is to be stitched, and means located adjacent said openings and extending inward from said portions for further compressing the material adjacent the point of entry of the needle in forming a stitch, and in a direction parallel to that in which said sections are moved in compressing the material.

6. A holder for receiving material such as coiled rope, braid or the like for the manufacture of flat articles such as rope soles, mats and pads, said holder being formed with separable complementary sections each formed with a portion

shaped to extend about an edge of material in said holder and provided with openings in said portion for the passage of a needle therethrough into work within the holder, said sections being movable toward each other to compress material between said portions in the direction in which the material is to be stitched, means located adjacent said openings and extending inward from said portions for further compressing the material adjacent the point of entry of the needle in forming a stitch, and in a direction parallel to that in which said sections are moved in compressing the material, and means for holding said sections in material clamping relation during stitching of the material.

7. A workholder for receiving and holding stranded material during stitching thereof embodying two complementary sections each of which has a track portion extending longitudinally of the holder adjacent opposite faces thereof, said sections having complementary edge defining portions shaped to extend about the stranded material and formed with openings therein through which a stitch forming element may pass, said openings being connected by slots 25

through which a thread connecting successive stitches may pass, ratchet teeth formed on said tracks, each of which teeth corresponds in length to the spacing of adjacent openings in said edge defining portions and means for connecting said sections together in material compressing relation.
